CLAIM

The ornamental design for a rowing machine, as shown and described.

DESCRIPTION

FIG. 1 is a front, right and bottom perspective view of a rowing machine, showing our design.

FIG. 2 is a rear, left and top perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a partial enlarged view of an area labeled 9 in FIG. 2.

FIG. 10 is a partial enlarged view of an area labeled 10 in FIG. 2; and,

FIG. 11 is a partial enlarged view of an area labeled 11 in FIG. 1.

The broken lines shown in the drawings depict portions of the rowing machine that form no part of the claimed design. In addition, the dot-dash broken lines in FIGS. 1, 2, and 9-11 depict the boundaries of the enlargements that form no part of the claimed design.

1 Claim, 11 Drawing Sheets
